UNITED STATES PATENT OFFICE

PHILIP JAMES KENT, OF DETROIT, MICHIGAN, ASSIGNOR TO CHRYSLER CORPORATION,
OF HIGHLAND PARK, MICHIGAN, A CORPORATION OF DELAWARE

VAPORIZING DEVICE FOR ENGINES

Application filed August 6, 1925. Serial No. 48,650.

It is the primary object of my invention to provide means for facilitating the starting of internal combustion engines, particularly in cold weather when vaporizing of the fuel 5 to be burned by the engine upon the starting thereof is difficult.

To accomplish this result, I have provided an electrical heating unit in the line ordinarily used for the air intake in such 10 devices, for the purpose of catching the unvaporized liquid fuel which normally flows downwardly through such passage and there vaporize it so that it may be carried to the cylinders of the engine in vaporized form. 15 In order that the heating unit may not interfere with the passage of air I have located the same at one side of the passageway but communicating with it.

With the above and other objects in view, 20 my invention consists of the arrangement, combination and construction of the various parts of my improved device as described in the specification, claimed in my claims and shown in the accompanying drawings, in 25 which:

Fig. 1 is a side elevation showing my improved device, certain of the parts being cut away and others being shown in section.

Fig. 2 is a sectional end view showing my 30 improved device and its location with respect to the air intake passage.

I have shown a conventional carburetor 10 having a fuel inlet passage 11 and connected through the passage 12 with the passage 13 such as is conventionally provided upon intake manifolds for internal combustion engines. The passages 12 and 13 are flanged as at 14 and 15 and secured together by capscrews or bolts 16. An air intake passage 17 extends at right angles to the carburetor 10 and communicates with the passage 12. A conventional butterfly valve 18 for choking the air supply is provided in the air passage 17 being pivoted as at 19 for operation by a lever 20 and rod 21, the latter extending to the usual dash of a motor vehicle.

An integral apertured boss or housing 22 is provided on a section of the passage 17, the 50 aperture being open to the air inlet passage

and being also connected therewith by a duct 23. A plug 24 is screwed into the bottom of the portion 22, the upper portion 25 of the plug being smaller than the aperture in the portion 22 so as to provide a space 26 between the wall of the aperture and the outside of the portion 25. Any unvaporized or liquid fuel passing from the carburetor 10 and failing to continue through the passage 12 and into the intake manifold, will flow through the passage 17 and into the space 26. This will be facilitated by reason of the fact that under normal operating conditions the butterfly valve 18 will be closed by the operator when he is endeavoring to start the engine in cold weather. Such fuel will pass through the plurality of openings 27 which are provided adjacent the bottom of the portion 25 into the interior of the portion 25. In this interior portion I provide a suitable absorbent material 28, such as asbestos, and within the asbestos I provide a coil of high resistance metal 29, which coil may be suitably connected through the plug 24 and the cap 30 thereon, with a wire 31 leading to a suitable source of electrical energy, such as a storage battery.

At the time of starting the engine the operator will close suitable connections so as to connect the wire 31 with its source of electricity so that the high resistance unit 29 will become heated, at which time the fuel which has been absorbed by the asbestos 28 will be heated to the vaporizing point and will pass off in the form of vapor through the passageway 32 into the passage 17, the passage 12 and thence into the intake manifold and the engine. Being thus passed in vaporized form, it will readily ignite in the engine and permit prompt starting thereof.

It will be apparent that all liquid fuel passing down the passage 17 will be drawn into the passage 26. Small quantities of such fuel will pass through the duct 23 and any excessive quantities thereof will pass directly into the chamber. It is further apparent that as fast as such fuel is collected it will be vaporized into the engine, and that the top of the portion 25, being higher than the connection between the passage 17 and the cham-

ber 26, prevents fuel flowing directly through the opening 32.

It will be obvious that various changes may be made in the arrangement, combination and construction of the various parts of my improved device without departing from the spirit of my invention, and it is my intention to cover by my claims such changes as may be reasonably included within the scope thereof.

What I claim is:

1. In combination, an intake manifold having a fuel passage and an air passage connected therewith, means permitting portions of unvaporized fuel from said fuel passage to enter said air passage, a receptacle connected with said air passage at one side thereof, a hollow member positioned in said receptacle and having its one end extended above the connection between said air passage and receptacle and entirely outside of said air passage, a space between the inner wall of the receptacle and the outer wall of the hollow member for the passage of fuel, means for feeding such fuel into said hollow member at the lower portion thereof and means for heating such fuel to permit its passage through the extended end of the hollow member to the manifold.
2. In combination, an intake manifold having a fuel passage and an air passage connected therewith, a receptacle having an opening through the wall of said air passage above the lower portion thereof, forming a communication between said chamber and said air passage, said air passage having a passage forming a communication between the lowest portion of said air passage and said receptacle, a heating element in said receptacle, and means entirely without said air passage for delivering fuel vaporized by said heating element into said air passage.

PHILIP JAMES KENT.
